UNITED STATES PATENT OFFICE.

ISRAEL GARON, OF DULUTH, MINNESOTA.

GARMENT-DRYING FRAME.

1,419,133.

Specification of Letters Patent. Patented June 13, 1922.

Application filed January 10, 1920. Serial No. 350,693.

To all whom it may concern:

Be it known that I, ISRAEL GARON, a citizen of the United States, residing at Duluth, in the county of St. Louis and State 5 of Minnesota, have invented certain new and useful Improvements in Garment-Drying Frames, of which I do hereby declare the following to be a specification.

My invention relates to garment drying frames, as for mittens and hosiery and has for its object the provision of an improved frame for drying mittens or hosiery during manufacture. One of the objections to the drying frames heretofore in use for such 15 purposes is that there has been no practical means for holding the wrist of the mitten or inverted top of the hose in order to prevent it from shortening by shrinkage during the drying process. Another objection to 20 prior drying frames has been that the palm portion or instep portion of the frame is substantially rigid, or non-contractible so that when the mitten or hose is pulled off the frame the wrist portion or ankle portion 25 must stretch to the width of the palm or to the width across instep and heel. A third objection to former drying frames is that the portion of the frame which projects into the thumb is substantially rigid, and 30 either cannot practicably be swung away from the palm portion in order to permit inspection of the side of the mitten thumb adjacent the palm, or else the thumb frame cannot be laid approximately flat against 35 the palm during the drying process so that the mitten thumb will dry in proper position. Another objection to former drying frames is that separate frames were required for right hand or left hand mittens. In 40 my invention all the above noted objections are avoided. My said invention consists of the constructions, combinations and arrangements of parts hereinafter described and claimed.

45 In the drawings, Fig. 1 is a front elevation of my said invention showing the herein-after described wrist clamp in operating or closed position. Fig. 2 is a side elevation of said invention, showing said wrist clamp 50 in open position and showing the herein-after described thumb frame swung outward in position to receive the thumb of the mitten, or to permit inspection thereof. Fig. 3 is an opposite side elevation of said invention 55 showing said wrist clamp in closed position; said thumb frame being swung into the verti-

cal plane of the herein-after described palm frame, and being concealed thereby. Fig. 4 is a rear elevation of my said invention, showing said wrist clamp in open position, 60 and showing said palm frame in contracted position. Fig. 5 is a fragmentary front elevation of a modified form of my invention showing the same as constructed for drying socks or stockings. Fig. 6 is a front elevation partly in central vertical section of a modified form of a portion of my said invention.

In the drawings, 1 is a base of any suitable form or structure, preferably cylindrical, whereby my invention is adapted to be mounted upon any suitable stationary or movable support. Extending upward from said base is a stationary post comprising a substantially straight portion 1^a and (in that 75 form of the invention adapted for the drying of mittens) an approximately comma-shaped portion 1^b. Pivotally mounted upon said base, as by a pivot 2, is a post comprising a substantially straight portion 2^a 80 and (in that form of the device adapted for drying mittens) an outwardly curved portion 2^b, the upper end of said outwardly curved portion 2^b being reduced in thickness and extending into a guide slot formed in 85 a transversely directed bar 1^c extending across said comma-shaped portion near its upper end. Said posts are connected together near their lower ends by a connecting bar 3, which bar is pivotally connected as at 90 3^a to one of said posts and is eccentrically pivoted at its opposite end to a shaft 3^b journalled in the other of said arms and provided with an operating handle 3^d. It will be observed that by operating said shaft by 95 means of said handle, the pivoted post 2^a—2^b will be rocked on its pivot so that its upper end will move along the bar 1^c toward the inner end thereof.

Journalled on each of said posts is a hold-fast or clamp comprising a shank portion 5 and a fork portion 5^a, which fork portion in operating position is adapted to straddle the adjacent post transversely and to closely engage or bind the wrist of the mitten or 105 top of the hose between itself and such post to prevent such wrist or top from being drawn upward by shrinkage during the drying process. Said holdfasts are held in operative position under tension by a spring or 110 springs of any suitable structure or method of application, as by a coiled tension spring

5^b attached at one end to one of said hold-
fasts and at the other end to the other of
said holdfasts, preferably at points a short
distance above their pivots, so that when said
5 holdfasts are retracted outwardly and down-
wardly the tension spring will move below
the pivots and keep the holdfasts in open
or retracted position. The pivots of said
holdfasts preferably extend through slots
10 1^a 2^c in said posts, so that they may be
adjusted in said slots to a higher or lower
plane on said arms according to the length
of the garment they are required to engage.

In the form of said invention designed for
15 drying mittens, I journal upon one of said
posts—preferably the stationary post—a
thumb frame 6, which may be swung on its
pivot forwardly or rearwardly beyond the
front or rear faces of said posts. If desired,
20 a brake of any suitable structure may be
provided to prevent said thumb frame from
accidentally changing from the position at
which it has been set by the operator. Said
brake may consist of a spring 6^a interposed
25 between the pivoted end of said thumb frame
and the opposite post. In the modified form
of said invention used for hosiery, said
thumb frame is omitted.

In said modified form, the lower or straight
30 portions of the posts, together with said base
and holdfasts, are the same as in the first
described form, but the upper or curved ends
of the posts are slightly modified in contour
so as to present the general vertical contour
35 of a foot, in which the curved portion 1^c of
the stationary arm resembles the outline of
the heel and toe and bottom of a foot, and
the curved portion 2^a of the movable arm re-
sembles the outline of the top of the foot.

40 If desired the straight portions 1^a, 2^a of
the posts may be separate from the curved
portions, and the curved portions may be
mounted thereon in any suitable manner, as
shown in Fig. 6 of the drawings, so that the
45 foot forms or the palm forms may be sub-
stituted for each other upon the same
straight portions. This may be done by re-
ducing the diameter of the lower ends of the
curved portions and inserting them in re-
50 cesses formed in the upper ends of said
straight portions, as will be readily under-
stood from this description.

Said frames whether used for drying mit-
tens or for drying hosiery may be mounted
55 upon any suitable support.

In operation, the holdfasts are first re-
tracted, and the garment to be dried is drawn
over the upper end of the drying frame. If
such garment be hose, it is of course inverted
60 so that the normal upper end of the hose is
lowermost and extends between the hold-
fasts. If such garment be a mitten, the mit-
ten drying form of such frame is used in-
stead of the hose drying form thereof, and
65 the thumb frame is inserted in the thumb of

the mitten at the same time that the palm
portion is inserted in the palm thereof. If
the pivoted post is not then in its outermost
position, it should be moved to such position
by means of said handle and connecting bar. 70
The holdfasts are then snapped into oper-
ative position to clamp the open end of the
garment to said posts. The operator may
inspect the dried garment while it is in posi-
tion on the frame, to see if there are any 75
places requiring mending. For this purpose,
he may rotate said frame in said carriage
socket, so as to inspect both sides of the gar-
ment. If a mitten, he may swing the thumb
frame a little away from the palm to inspect 80
the inner side of the thumb. The operator
then by means of said handle and connecting
bar swings said pivoted post on its pivot
toward said stationary post, which contracts
85 the widest portion of such frame, or loop
formed by said posts, as across the palm of
the mitten frame or as across the heel and
top of the instep of the hosiery frame, there-
by permitting the garment to be drawn off 90
the frame without materially, if at all, 95
stretching the narrower parts of said gar-
ment out of shape.

It will be observed that a material advan-
tage of the mitten drying form of said frame
is derivable from the fact that the same 95
frame is adaptable for use with either right-
handed or left-handed mittens, by reason of
the fact that the same thumb frame can be
swung out to either side of the palm frame.

It is obvious that my said invention may 100
be modified or altered in certain details with-
in the spirit and scope of certain of my
claims.

What I claim is—

1. In a garment drying frame, the combi-
nation with a suitable base, of a stationary
post extending therefrom, said post having
a substantially straight lower portion and
a curved upper end; a second post pivotally
connected to said base and extending there-
from parallel to said stationary post for
part of its length, said pivoted post having
a curved upper end adapted to meet the
upper terminal of said stationary post, said
posts being adapted in operative position to
cooperate to form a loop, and means for re-
tracting said pivoted post toward said sta-
tionary post, whereby the transverse di-
ameter of said loop is contracted. 115

2. In a garment drying frame, the combi-
nation with a suitable base, of a stationary
post extending therefrom, said post having a
substantially straight lower portion and a
curved upper portion, a second post pivot-
ally connected to said base and extending 125
therefrom approximately parallel to said
stationary post for a part of its length, said
pivoted post having a curved upper end
adapted to meet the upper terminal of said
stationary post, said posts being adapted in 130

operative position to cooperate to form a loop, and means for clamping the fabric of a garment to said posts.

3. The combination with a suitable base, 5 of a stationary post extending therefrom, said post having a curved upper end, a second post pivoted to said base and extending therefrom approximately parallel to said stationary post for a portion of its 10 length, said pivoted post having a curved upper end adapted to meet the upper terminal of said stationary post, said posts being adapted in normal position to cooperate to form a loop and a thumb-shaped 15 member pivoted to a suitable support and adapted to be swung on its pivot forward or back through said loop.

4. The combination with a suitable base, of a stationary post extending therefrom, a 20 second post pivoted to said base and adapted in normal position to cooperate with said stationary post to form a loop, a thumb-shaped member pivoted to said stationary post and adapted to be swung on its pivot 25 forward or back through said loop, and means mounted on said posts for clamping thereto a portion of the garment to be dried.

5. The combination with a suitable base, of a stationary post extending therefrom, a

second post pivoted to said base and adapted 30 in normal position to cooperate with said stationary post to form a loop, means for swinging said pivoted post on its pivot toward said stationary post whereby the loop formed by said posts will be contracted in 35 diameter near its upper end.

6. The combination with a suitable base, of a stationary post, a second post pivoted to said base and adapted in normal position to cooperate with said stationary post to form 40 a loop, clamping means carried by each of said posts, said means comprising a shank portion pivoted at its lower end to the corresponding post and a forked portion formed on or secured to the free end of such shank 45 portion, said forked portion being adapted to straddle the corresponding post and to clamp thereto the intervening edge of a garment to be dried, and means for holding said shanks in operative position under tension. 50

In testimony whereof, I hereunto affix my signature in presence of two witnesses.
